SAFETY GUARD

Thomas Digman, Pittsburgh, Pa.

Application August 24, 1938, Serial No. 226,548

2 Claims. (Cl. 2-11)

This invention relates to a safety device and particularly to an improved safety guard for the use of workmen operating chipping hammers and the like.

Heretofore, operators of pneumatic chipping hammers and the like usually wore goggles to protect their eyes from injury, due to flying chips or other foreign particles. While goggles were usually satisfactory and protected the eyes, they did not protect the face and other parts of the body of the operator from injury, nor nearby workmen engaged in other duties. Also, it was necessary for the chipping hammer operators to wear goggles the greater part of the day, and goggles become quite uncomfortable to the wearer after continuous use over such a long period of time.

It has been proposed to attach safety guards to chipping hammers and the like, but such guards soon became loose and out of adjustment, due to the vibration of the hammer, and were very troublesome; also, guards attached to the hammers oftentimes interfere with the operation thereof, thereby tending to discourage their use entirely, which, of course, defeats the purpose for which they are intended.

According to the present invention, there is provided an improved safety guard which is safe and easy to use and, when once adjusted to position, cannot be easily shifted therefrom.

It is an object of the present invention to provide a simple and inexpensive safety guard which will encourage its use and protect other workmen in the immediate vicinity as well as the operator. It is another object of the invention to provide a safety guard for use with chipping hammers and the like which will deflect the chips or other foreign particles downwardly, away from the work, immediately after they leave the surface thereof, thereby eliminating the danger of the chips piling up and obscuring the work.

It is a further object of the invention to provide a safety guard which will permit a clear vision of the working tool and the work at all times and, at the same time, provide a guard which is effective in its use.

Various other objects and advantages of this invention will be more apparent in the course of the following specification and will be particularly pointed out in the appended claims.

In the accompanying drawing there is shown, for the purpose of illustration, one embodiment which my invention may assume in practice.

In this drawing:

Figure 1 is a pictorial view of the improved

safety guard of my invention, showing it attached to the operator's arm as in use;

Figure 2 is an enlarged plan of my improved safety guard;

Figure 3 is a section taken on the line III-III 5 of Figure 2; and,

Figure 4 is a plan showing a modified bracket for attachment.

Referring more particularly to the drawing, the improved safety guard of my invention comprises a deflecting shield 2 consisting of a curved frame 3 preferably made from sheet metal having an opening in the center thereof which is covered by a transparent material, preferably a wire mesh screen 4, which may be welded, soldered or otherwise attached to the frame in any suitable manner, with the mesh of the wire being small enough to prevent chips or foreign particles from coming therethrough. A $\frac{1}{4}$ inch wire mesh screen has been found to be satisfactory for most purposes.

There is arranged on the top side of the frame 3 a bracket 5, which may be riveted, welded or secured to the frame in any other suitable manner, having a hole therein which is adapted to receive a supporting rod 6. The rod 6 is preferably curved, as shown in Figures 1 and 2, or it may be straight with the end turned outwardly, as shown at 6a in Figure 4, or it may be of any other suitable shape. The bracket member 5 30 carries an adjusting set-screw 7, preferably a thumb screw, for the purpose of adjusting and holding the frame in its adjusted position on the end of the rod.

The opposite end of the rod 6 is adjustably positioned in an opening of a bracket 8 carried by a relatively wide strap 9, preferably made of leather, which is adapted to be attached to the arm of the operator, just above the wrist, and held thereon by means of a buckle arrangement 40 10. The bracket member 8 also carries an adjusting set-screw 12, preferably a thumb screw, for adjusting and holding that end of the rod in the bracket.

It will be seen that the thumb screw 7 in the bracket 5 and the thumb screw 12 in the bracket 8 will permit suitable adjustment of the rod and shield sideways; also, these screws will permit adjustment of the shield on the rod 6 relative to the end of the chipping or working tool and the work to be chipped or worked upon.

There is shown a leather strap for attaching the safety guard to the arm of the wearer but it will be understood that any suitable means of attachment may be provided, such as a re-

silient bracelet-like metallic strap. It is desirable that preferably a rod or flat member be used to connect the shield to the arm strap as such a member can be easily bent to conform to the angle which the hand may take on the hammer and thereby may be comfortably adjusted to the arm of any particular operator.

As a result of my invention, it will be seen that I have provided an improved safety guard for the use of workmen operating chipping hammers which will not interfere with the operator or the holding of the hammer, and if the operator desires to inspect the work, it is necessary only to move his hand from the hammer, thereby allowing a clear view of the work. Furthermore, it will be seen that accidents to fellow workmen, as well as to the operator, will be greatly diminished by the use of the improved safety guard of my invention.

While I have shown and described one embodiment of my invention, it will be understood that this embodiment is merely for the purpose of illustration and description, and that various other forms may be devised within the scope of my invention, as defined in the appended claims.

I claim:

1. A safety guard for the use of workmen operating chipping hammers and the like comprising a frame, a wire mesh screen arranged within said frame for deflecting foreign particles and

enabling the workman to view the work-piece therethrough, a strap member for attachment to the arm of the workman, an inherently rigid outwardly extending supporting member extending between said frame and said strap, a bracket member carried by said frame for movably attaching one end of said rigid supporting member thereto, a set screw associated with said bracket for holding the end of said rigid supporting member adjustably therein, another similar bracket member carried by said strap member for movably attaching the opposite end of said rigid supporting member thereto, and a set screw associated with said last mentioned bracket for holding that end of said rigid supporting member adjustably therein.

2. A safety guard for the use of workmen operating chipping hammers and the like comprising a deflecting shield adapted to be positioned over the working tool of the hammer, a strap for attachment to the arm of the operator, an inherently rigid outwardly extending shield supporting member extending between said deflecting shield and said strap, adjustable means for connecting one end of said rigid member to said strap, and adjustable means for connecting the opposite end of said rigid member to said shield.

THOMAS DIGMAN. 30
